UNITED STATES PATENT OFFICE

HARRY W. MOORE, OF DAYTON, OHIO

DESIGN FOR A GOLF BALL EMBOSSE

Application filed May 29, 1931. Serial No. 40,026. Term of patent 7 years.

To all whom it may concern:

Be it known that I, HARRY W. MOORE, a citizen of the United States, residing in the county of Greene, near the city of Dayton, in the State of Ohio, have invented a new, original, and ornamental Design for a Golf Ball Embosser, of which the following is a specification, reference being had to the accompanying drawing, forming part hereof.

The figure is a perspective view of a golf ball embosser, showing my new design.

I claim:

The ornamental design for a golf ball embosser, as shown.

HARRY W. MOORE.
